RAILWAY CAR TRUCK

James A. Shafer, East Cleveland, Ohio, assignor
to National Malleable and Steel Castings Company, Cleveland, Ohio, a corporation of Ohio

Application April 3, 1941, Serial No. 386,683

3 Claims. (Cl. 308—38)

This invention relates to railway car trucks, and more particularly to means for limiting angular movement of the side frames relative to the car axle.

Certain types of railway car trucks are made with the bolster and side frames separate, that is, they are of the non-rigid variety. On some of these trucks the side frames are joined together only by the bolster and the axles and there is looseness in the parts that permits the side frames to angle relative to the bolster and axles. In other trucks the side frames are joined together beneath the bolster by a spring plank which is either riveted to the side frame or fits over dowels on the spring seating portion of the side frame. After these latter types of trucks have been in service a while the rivets loosen or the connections between the dowels and spring plank become worn, and the extent to which the side frame can angle with respect to the bolster and axles is increased. When this angled condition occurs the truck is said to be out of square.

The trucks can go out of square only a certain amount as the angling of the bolster relative to the side frames is limited by the closeness of fit between these parts. However, the contacting surfaces on the side frames and bolster, or between the side frames and spring plank where used, are not always located so as to limit said angular movement to such an amount that would prevent stresses being placed on other parts of the truck. This is particularly true when the parts have become worn. I have found that quite frequently, especially in spring plankless trucks, the thrust lugs on the journal bearing member have broken off due to the stresses imposed on this member which it was not designed to resist.

An object of the present invention is therefore to provide means in the journal box to prevent stresses other than thrust stresses from being placed on the bearing thrust lugs when the truck tends to go out of square.

A further object of the invention is to provide means to limit angular movement of the wedge member so as to prevent undesired stresses being placed on the bearing member.

Other objects and advantages will be referred to in connection with the accompanying drawings, in which:

Figure 1 is a horizontal sectional view through a journal box embodying the invention, taken on line 1—1 of Figure 2.

Figure 2 is a transverse vertical sectional view, taken on line 2—2 of Figure 1.

Figure 3 is a longitudinal vertical sectional view of the upper part of a journal box embodying the invention.

Figure 4 is a horizontal sectional view, taken on line 4—4 of Figure 2.

Figure 5 is a horizontal sectional view through a journal box, showing a modification of the invention; and

Figure 6 is a view showing the bolster and axles angled with respect to a side frame, one of the journal boxes being shown in horizontal section.

It will be observed from Figs. 2 and 3 that the bearing member 10 which rests on journal 11 has an upper portion 12 formed by sloping surfaces 13 and horizontal surface 14. The wedge member 15 has a recess on its under side formed by surfaces 16, sloping similarly to surfaces 13 on the wedge, and a horizontal surface 17 which joins surfaces 16. A slight clearance is provided between surfaces 13 and 16 so as to assure seating of surface 17 on surface 14. It will therefore be apparent that by this interfitting of the members, angular movement of journal 11 relative to the journal box will cause substantially simultaneous angular movement of bearing member 10 and wedge 15.

Projecting inwardly from each side wall of the box is a stop lug 18 adapted to be engaged by the usual thrust lugs 19 extending laterally from bearing member 10. As the journal moves to the right, as viewed in Fig. 3, the collar 20 of the journal contacts end 21 of the bearing member and moves the latter until lugs 19 engage stop lugs 18. Movement of the journal relative to the box is thus limited in one direction by the engagement of these lugs. As the journal moves to the left, as viewed in Fig. 3, fillet 22 of the journal engages a corresponding surface 23 of the bearing member until lug 24 of the latter member engages the inner end of wedge 15. The wedge then moves with the journal and bearing member until end surface 25 of the wedge engages lugs 26 depending from the upper wall of the journal box. Adjacent lugs 18 are stops 27 having surfaces 28 adapted to engage the side of the wedge to limit lateral movement thereof relative to the box.

In Fig. 6 is shown the effect of out of square running of a truck having conventional journal boxes integral with the side frame. The axles have been angled to such an extent that further angling of either axle relative to its journal box is resisted by the bearing member and wedge

acting as an integral or single member in engagement with the box at points *a* and *b*. At point *a* the engagement is between end surface 25 of the wedge and lug 26 of the box, while at point *b* the engagement is between lug 19 of the bearing member and stop lug 18 of the box. The bearing and wedge under these conditions act as a single member due to the V-shaped engagement between the members, in conjunction with the engagement between lug 24 and the end surface of the wedge. Therefore, regarding the members as being integral, point *a* in effect becomes a pivot point, while point *b* becomes the point of application of the force acting to resist further pivoting of the axle. The force which has drawn the truck out of square is acting at the opposite end of the axle at right angles thereto and is caused by the flange drag which occurs between the flange of the wheel at that end and the rail. It will be apparent that since this latter force acts at the opposite end of the axle its moment arm about point *a* is considerably greater than the moment arm of the reacting force at *b* and that therefore said reacting force on lug 19 may attain excessive proportions. The wedge and journal box being made of steel are strong enough to withstand the stresses to which they are subjected under the above conditions. The bearing member, however, is made of brass, and lugs 19, while adequate to resist normal lateral thrusts against stops 18, are not strong enough to resist an excessive force as may be imposed thereon under the aforesaid conditions when the truck goes out of square, resulting in failure of the lug in which stresses are thus induced. The truck may go out of square and thus produce the condition above described during travel of the car around a curve or on a straight track at high speed. When the truck goes out of square on a curve it is maintained in that position throughout the length of the curve so that under this condition only one of the lugs 19 is engaged, as is shown in Fig. 6. Furthermore, the force against lug 19 acts throughout the curve or until the lug fails. At high speeds on a straight track it has been found that under certain conditions the side frames of a truck may see-saw back and forth constantly, that is, one moment the truck will go out of square with one frame in the lead and the next instant with the opposite frame in the lead. Under these conditions lugs 19 will alternately be subjected to an impact by contact with stops 18. The stresses thus produced in the lugs during travel of the truck along curves or on straight track at high speeds have caused the failure of either one or both of them.

In order to limit the angular movement between the bearing and wedge members and the journal box, the box is provided with horizontally disposed stops 30 adjacent sides 31 of the wedge member and conforming generally in outline thereto. These stops are adapted to limit the angular movement of the wedge to such a position that at no time can the bearing move to a position in which lug 19 thereof will serve to resist angling of the axle and thereby be subjected to excessive stresses. In Fig. 1 is illustrated the effectiveness of stops 30 in limiting the angling of the wedge and consequently the angling of the bearing member and of the axle. Here, the axle has been angled to a position in which the sides of the wedge member engage stops 30 at *c* and at *d*, so that further angling

of the axle is impossible. Lug 19 of the bearing member may, as shown, engage stop 18 of the box. However, when such a condition occurs, the end surface 25 of the wedge member does not engage stops 26 of the box, and therefore it will be evident that the only force to which lug 19 can be subjected will be one directed longitudinally of the axle as is caused by lateral movements of the truck. This latter force is of much smaller magnitude than that which acts on lug 19 when the wedge member pivots about some point on stop 26, as previously described. Furthermore, if end surface 25 of the wedge is moved into engagement with stop 26 the only force which can act on lug 19 will still be one directed longitudinally of the axle due to the aforesaid engagement between the wedge and stops 30, as at *c* and *d*.

The undersurface 32 of stops 30 is sloped downwardly toward the side walls of the journal box so that in the event the box is accidentally raised and angled to a position in which the top surface of the wedge member engages surface 32, the slope thereof will act to cause the box to return to normal position.

In the form of the invention shown in Fig. 5 the journal box is of the usual construction. The wedge member is the same as in the previous embodiment but is provided with a lug 35 at one end thereof which is received between the ends of stops 26 and is adapted to engage end faces 36 thereof during angling of the wedge. This engagement in conjunction with engagement of the wedge with surface 28 of stop 27, as at *f*, will effectively limit angling of the wedge and also the bearing member, and lugs 19 will not be called upon to resist angling of the axle as the truck tends to go out of square. Lugs 19, therefore, as in the previous embodiment, can be subjected only to lateral thrusts against stops 18, that is, they can be subjected to forces acting in a direction longitudinally of the axle.

It will be clear that my invention provides positive means for protection of the bearing thrust lugs against forces acting thereon other than those which they are designed to withstand. In addition, a car truck embodying the invention will run out of square only to the extent of the limited amount of angling permitted between the wedge and the journal box.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. A journal box having interfitting wedge and bearing members adapted to support said box on a journal, said members being adapted to move substantially as a unit angularly of said box, stop lugs in said box at the sides of said members, said bearing member having projections on the sides thereof adapted to engage said lugs to limit longitudinal movement of said bearing member relative to said box in one direction, and stop means on each side of said stop lugs having surfaces extending longitudinally of said box adapted to be engaged by said wedge member to limit angling of said members in a horizontal plane.

2. A journal box having interfitting wedge and

bearing members adapted to support said box on a journal, said members being adapted to move as a unit angularly of said box, stop lugs in said box at the sides of said members, said bearing member having projections on the sides thereof adapted to engage said lugs to limit longitudinal movement of said bearing member relative to said box in one direction, and stop means at the forward and rear ends of said box adjacent the sides of said wedge member, said means being adapted to engage diagonally opposite sides of said wedge member to limit angling thereof a predetermined amount.

3. A journal box adapted to receive a journal, wedge and bearing members, said box comprising a pair of side walls, means intermediate the ends of said box projecting inwardly from said walls and adapted to limit movement of said wedge member laterally of said box, and longitudinally extending stop means adjacent said first named means projecting from said walls and adapted to maintain said wedge member substantially in longitudinal alignment with respect to said box, the under surface of said means being sloped upwardly from said side walls.
- 5 and adapted to limit movement of said wedge member laterally of said box, and longitudinally extending stop means adjacent said first named means projecting from said walls and adapted to maintain said wedge member substantially in longitudinal alignment with respect to said box, the under surface of said means being sloped upwardly from said side walls.
- 10 JAMES A. SHAFFER.
